UNITED STATES PATENT OFFICE

2,399,571

CIRCULATING COMPRESSOR

Albert M. Porter, Newton, Kans.

Application October 9, 1944, Serial No. 557,837

2 Claims. (Cl. 230—184)

This invention relates to a circulating compressor and has for its principal object a structure comprising a cylinder or cylinders and their respective pistons and rods connecting the pistons to a crank to actuate the pistons, all being housed within a casing comprising a circulating chamber for air and hydraulic substance and a crank-case, said circulating structure to function as a medium between a source of power and a power driven by the compressor.

A further object of this invention is to construct a compressor having a plurality of pumping cylinders placed within a circulating chamber for substance to be compressed as a power transmitting its energy through pipes to an engine or engines optionally which in turn will function as another driving medium for machinery or other uses for which power is required to actuate the same.

A further object of this invention is to construct a compressor in such a way that its energy has the capacity to create circulation of a preferred substance therethrough continuously or to store the same under compression to a predetermined degree of force and automatically retain the same uniformly.

A still further object of this invention is to position a series of ball valves in spaced relation around the upper extremity of the pump cylinder to communicate with a circulating chamber and outward through other ball valves that are grouped directly over the upper ends of each cylinder to discharge force impounded therein through last said ball valves into a discharge chamber that exhausts through a pipe or pipes through which the power is transmitted, and all of said ball valves being inclined to reseat by gravity action during short periods of idleness due to pulsative strokes of the pistons.

These and other objects will hereinafter be more fully explained reference being had to the accompanying drawings forming a part of this specification and in which like characters will apply to like parts in the different views.

Referring to the drawings:

Fig. 1 is a vertical section through the compressor, the cylinders, air supply, connecting rods, and crank being in elevation.

Fig. 2 is a top plan view of the compressor.

Figs. 3, 4, 5, and 6 are cross sections taken on their respective lines correspondingly as shown in Fig. 1, looking in direction of the arrows.

Fig. 7 is a side elevation of the compressor and a motor as connected by a drive-shaft and safety valve governing arm.

As a more concised description of the invention

it will be seen that the same comprises a circulating chamber and crank case having side walls 1, a head 2, and a bottom 3, said chamber and crank case being divided from each other by a horizontally disposed web element 4.

Positioned in the circulating chamber is a pair of cylinders 5, said cylinders at their lower extremities communicating with the crank case whereby pistons 6 in the cylinders are oiled by a splash system created by a crank 7 journalled in its case and the said crank being connected to the pistons by rods 8 whereby an efficient dual pumping system is arranged and being actuated by an engine 9, the drive shaft 10 of which is secured to the crank shaft by a flanged joint connection 11, but not restricted to such connection alone.

Detachably connected to the circulating chamber is a return pipe 12 as a conductor for air or hydraulic substance through the system, and oppositely positioned in the circulating chamber is an air supply pipe 13 upwardly extending and having a valve 14 to open and close the pipe wholly or in part as desired to automatically supply an air deficiency in the system chamber, and the said pipe 14 at its upper extremity has a conventional aircleaner 15 secured thereto to restrict sediment from entering the chamber, whereby a desired amount of air is introduced into the chamber should the same be hydraulically charged for pneumatic action to neutralize the shock of pulsative strokes of the pistons, otherwise if the system was charged solid with water, oil, or the like, the cushion valve would be void. It will be seen that a series of ball valves 16 surround each

cylinder in spaced relation and adapted to communicate with the circulating chamber through their respective apertures A while cavity B of each said valves extend upward and outward through the upper side of said head and each of said cavities have a slot C to communicate with their respective cylinders whereby substance is drawn from the circulating chamber into the cylinders by a downward stroke of the pistons and then ejected outward through apertures of ball valves 16 grouped in another head 18, said groups being in concentric registry with their respective cylinders, and the last said groups of ball valves having a plate 20 lying on the upper side of said head 18 and through which is positioned groups of apertures 21 that are in registry with last said ball valves in the said head 18 whereby the said ejected substance is free to enter a chamber 22 lying between plate 20 and a head 23, said head having a flange D to space the head body from the

55 said plate to form the chamber.

The said head 23 has an outwardly extending nipple 24 at one end thereof and being threaded externally to threadedly engage an outward flow pipe 25 as a conductor for substance to a storage tank or engine as power actuating means therefor. It will be seen that heads 2, 18, 23, and plate 26 are drilled in registry as at D, and being secured together oil tight by cap screws 26, and the crank case bottom being secured to the side walls oil tight by cap screws 21.

Positioned on head 23 and upwardly extending is a valve structure comprising a tubular cylinder 28, said cylinder being open at one end and having a flange as at E to seat on the head and being secured thereto by cap screws 29, said head 23 being apertured as at 30 and in axial registry with the opening, the other end of the cylinder having an apertured head 31 to close the same. Positioned in the cylinder is a valve structure comprising a stem 32 having a piston 33 thereon to cover the aperture 30, and a coil spring 34 is wound on the stem so that one end thereof seats on the piston while the other end seats on the apertured head to clamp the piston to close engagement over the aperture, the stem extending outward through the aperture of the head and having one end of a bell crank 35 rockably connected thereto by a link 36 while the elbow of the crank is rockably connected to the upper end of an arm 37, the lower end of which is integrally joined to the cylinder. Rockably connected to the other end of the bell crank is an arm 38 that extends to and rockably connects to a butter-fly lever 39 of a conventional internal combustion engine carburetor whereby the speed of the engine is automatically controlled by the compressor as the said tubular valve structure communicates with chamber 22 that contains substance that is normally compressed which in turn acts upon the said tubular control valve that functions as a safety device for the compressor. Positioned in the cylinder adjacent its apertured head is an aperture 40 to function as a breather for the valve piston.

Such modifications may be made as lie within the scope of the appended claims.

Having fully described my invention what I claim as new and desire to secure by Letters Patent is:

1. In a circulating compressor of the class described comprising a crankcase and a crank in the case, and an engine to turn the crank, a cylinder having a piston and rod connecting with the crank, the cylinder having a plurality of ducts in spaced relation around the cylinder at its upper extremity, a circulating chamber surrounding the cylinder from a spaced distance downward to a head surrounding the head externally and an intake for the circulating chamber, gravity actuated ball valves to communicate with the cylinder through its ducts, while the balls are positioned in a lower plain seating in openings that communicate with the circulating chamber, a head to close the upper extremity of the cylinder and its respective ball valves and duct openings, the head being of suitable thickness, and a cluster of gravity actuated ball valves concentrically positioned to communicate with the cylinder for air exclusion outward through the head, a plate to lie on the head at its upper extremity and being secured thereto, said plate having a series of clustered ports, each cluster being in registry with the last said gravity actuated ball valves, a flanged head, the flange seating on the plate as spacing means for the head from the plate whereby an exhaust chamber is formed to receive air forced therein through the clustered apertures, and an exhaust pipe for the chamber.
2. In a circulating compressor as recited in claim 1, a safety device for a predetermined pressure, said device being seated on the flanged head and comprising a tubular cylinder having a head to close one end, the other end being open to communicate with the exhaust chamber through an opening in the head of the said chamber, a spring tensioned piston to resist a predetermined force within the compressor, the piston having a rod extending axial through the tubular cylinder and outward from its head, a series of levers rockably connected and to said rod as controlling means for the engine fuel whereby the force of the engine is automatically controlled to maintain a uniformity of pressure in the compressor.

ALBERT M. PORTER.
